Application June 24, 1950, Serial No. 170,215

12 Claims. (Cl. 340—176)

1

This invention relates to selecting networks, and more particularly to networks of this type making use of the properties of unilateral conductors.

There are many applications in which it is desired to excute unique combinations of operations whenever a predetermined set of stimuli occurs. Where considerable amounts of power are available and the time for setting up and carrying out any of the predetermined sequences is relatively long, relay coils actuating sets of contacts may be used for this purpose. When the number of choices is relatively small and the speeds of operation required are of the order of a few hundred per second, it is possible to employ resistance matrices for networks to carry out the desired selecting operation. When the ultimate in speed, by today's standards, is required it has been found that the unilateral conducting properties of germanium crystal diodes and the like connected into selecting matrices may be employed with material advantage. The use of such unilateral conductors, however, because of their special properties, requires consideration of several aspects of circuit performance which are not immediately obvious, but which will be discussed below.

One of the objects of the invention is to provide a new and novel selecting network particularly adapted for high speed operation.

Another object of the invention is to provide a new and novel selecting network adapted for actuation from pairs of alternatively operative electric valves.

A further object of the invention is to provide a new and novel selecting network delivering normalized signals to the associated control channels.

Still another object of the invention is to provide a new and improved apparatus for developing arbitrary output stimuli combinations in response to equally arbitrary input stimuli combinations.

Yet a further object of the invention is to provide a new and improved network for the energization of circuits through unilateral conductors reducing the undesirable effects of back resistance.

Other objects and advantages of the invention will in part be described and in part be obvious when the following specification is read in conjunction with drawings in which:

Figure 1 illustrates schematically a selecting network driven from a storage register including electric valves,

Figure 2 illustrates schematically a selecting network combining the indications of banks of electric valves to select unique elements,

Figure 3 illustrates schematically a selective network and storage register of somewhat greater capacity than is illustrated in Figure 1,

2

Figure 4 illustrates schematically a selecting network actuated from a counter chain,

Figure 5 illustrates in schematic form apparatus combining the selecting action of the apparatus of Figures 1, 3, and 4 in conjunction with an additional selecting network, and

Figure 6 illustrates in schematic form a selecting network converting single line indications into multiple channel stimuli.

10 The schematic diagram of Figure 1 illustrates the cooperation of a number of flip-flops with a selecting network incorporating diodes for separately exciting output conductors, one at a time, depending upon the combinations set up in the flip-flop register.

One of the coupling valve and flip-flop arrangements will be described in detail, it being understood that the balance of the circuits are essentially the same and function in substantially the same manner. A flip-flop 20 is excited from the coupling valve 21 having a control electrode 22 connected, through capacitor 23, with a point on the transmission line 24. The line 24 may comprise any of the conventional transmission line structures, and is here illustrated as made up of a series of sections including series inductance and parallel capacitance and is terminated in its characteristic impedance 92. For convenient reference, all supply buses will be identified with 20 a number corresponding with their voltage, even numbers being employed for positive voltages and odd numbers for negative voltages. In addition, the control electrode 22 may be returned to a negative supply bus 11 through a resistor 25, which is shunted by diodes 26 so poled as to prevent the development of negative-going surges across the resistor 25. The valve 21 is further provided with a cathode 27 returned to ground and an anode 28 connected with a positive supply bus 120 through resistor 29. A space charge grid 30 is connected with a positive supply bus 60, while the inner control electrode 31 is connected with a setup signal input terminal 32 through capacitor 33 and to a negative supply bus 7 through the resistor 34.

Signals appearing across the resistor load 29 are impressed on the control grid 42 of the flip-flop 43 through a capacitor 37, whose grid end is returned to the supply bus 41 through resistor 38.

50 The valve 43 may be of the type commercially designated 6AS6 and is further provided with an anode 44 returned to ground through a load resistor 45 and a cathode 46 connected with the negative supply bus 101.

55 Flip-flop 20 also includes a valve 47 having an anode 48 connected with ground through the resistor 49 and a cathode 50 returned to the negative supply bus 101. A resistance-capacitance network 51 connects the auxiliary control electrode 52 of the valve 43 with the anode 48 of the valve 47, while the auxiliary control electrode

39 of the valve 47 is connected through the resistance-capacitance network 53 with the anode 44 of the valve 43. Space charge grids 54, 55 are connected with the negative supply bus 41 and the inner control electrode 40 of the valve 47 is connected to the clearing bus 56, which is returned through a resistor 57 to the negative supply bus 101.

A single-pole double-throw clearing switch 58 is provided, having the normally disengaged pole 10 connected with the clearing bus 56 and its movable contact connected through capacitor 59 with ground. The normally engaged pole is linked with the negative supply bus 101.

The selecting network is not actuated directly from the flip-flop 20, but rather through the intermediate function table driver valves 62 and 63. The control grid 64 of the valve 62 is connected through resistance 66 to the anode 44 of the flip-flop valve 43, while its anode 68 is connected through the load resistor 70 with the positive supply bus 120. Unilateral conductors, which may be germanium crystal diodes for high speed operation, or, for lower speed operation, the well-known copper oxide, selenium or magnesium sulfide types, are connected between the anode 68 and the lines 100 and 102 at 103 and 105 with the polarity indicated. A unilateral conductor 72, poled to limit negative excursions of the anode 68, is connected between the said anode 68 and the negative supply bus 17. A similar unilateral conductor 74 may be connected between the anode 68 of the valve 62 and ground in series with the resistor 76, poled to limit positive excursions. The space charge grid 78 of the valve 62 may also be connected with ground, while the cathode 80 is returned to the negative supply bus 61.

Similar connections link the control electrode 65 of valve 63 with the anode 48 of the flip-flop valve 47 via the resistor 67. The space charge grid 79 of valve 67 is similarly connected with ground, while its anode 69 is connected with the positive supply bus 120 through load resistor 71 and joined to the conducting lines 104, 106, by unilateral conductors at 107 and 109, connected with the polarity indicated. In addition, the anode 69 is connected through the negative excursion limiting diode 73 with the negative supply bus 17 and with ground through the positive excursion limiting diode 75 in series with the resistor 77. The cathode 81 is connected with the negative supply bus 61.

The lines 100, 102, 104 and 106 are respectively connected through intermediate circuits represented generally by the load resistors 95, 96, 97, and 98 returned to the negative supply bus 11.

A further coupling valve 83 is connected with the flip-flop 82 comprising the valves 86 and 87 situated in circuits which may be identical with those previously described. A function table driver valve 84 is coupled to the anode circuit of the flip-flop valve 86 and the anode 88 of the valve 84 is connected with the load impedance 110 and conducting lines 100 and 104 by unilateral conductors at 111 and 112, poled as indicated. A similar function table driver valve 85 is connected to the anode circuit of the valve 87 of flip-flop 82, the anode 89 of the valve 85 being connected with the load impedance 113 and with the conducting lines 102 and 106 through unilateral conductors, poled as shown, at 114 and 115.

The auxiliary control grid of the valve 83 is coupled with the transmission line tap 91 and 75

the inner control grid of the coupling valve 83 is linked to capacitor 33 and thence to the setup signal terminal 32. The clearing bus 56 is connected with the inner control electrode of the valve 87 in the flip-flop 82.

The reference states of the valves making up the apparatus of Figure 1 are as illustrated, the shaded valves being conducting. When it is desired to place this equipment in operation, the existence of the reference state is insured by actuation of the momentary switch 58 which disconnects the capacitor 59 from the negative supply bus 101 and connects it with the clearing line 56, to impress a cutoff voltage on the inner control electrodes of valve 47 in the flip-flop 20 and the valve 67 in the flip-flop 82. The interruption of current flow through the valve 47 develops a positive-going voltage at the anode 48, which is coupled through the resistance-capacitance network 51 to the auxiliary control electrode 52 of the valve 43, permitting the flow of current to the anode 44 to reduce its potential and thereby impress a relatively negative voltage through the resistance-capacitance network 53 on the auxiliary control electrode 39 of the valve 47, which maintains the valve 47 nonconductive, while conduction continues through the valve 43. The inner control electrode 42 of the valve 63 plays no part in this action, as it is returned through a resistor 36 to a bus positive with respect to the cathode supply bus 101, whereby a steady flow of current between the cathode 46 and the space charge grid 54 is permitted.

The actuation of the switch 58 to impress a negative impulse on the clearing line 56 insures the establishment of conduction through the valve 86 of the flip-flop 82 and the nonconductivity of the valve 87 of said flip-flop 82 in substantially the same manner. When these circuit conditions prevail, the function table driver valves 62 and 84, whose control electrodes are linked with the anode circuit of the conductive side of flip-flops 20 and 82 respectively, are rendered nonconductive, while the function table driver valves 63 and 85, having their control electrodes linked with the anode circuits of the nonconductive side of the flip-flops 20 and 82, respectively, are conductive.

The clamping action of the negative excursion limiting diodes restrains the anodes 69 and 89 at minus seventeen volts which, it will be noted, makes the cathodes of the diodes at 107, 109, 114, and 115 negative with respect to their associated anodes, producing a flow of current therethrough shifting the potentials of lines 102, 104, and 106 to a value of approximately minus 17 volts.

The absence of conduction in the anodes of function table driver valves 62 and 84 permits the associated anodes 68 and 88 to rise to a potential somewhat more positive than ground due to the clamping action of the positive excursion limiting diode 74 in series with the resistor 76 in the anode circuit of the valve 62 and its counterpart in the anode circuit of valve 84. The lines associated with the loads 78 and 110 therefore become positive. This makes the potential of the cathode of the unilateral conductor indicated at 105 more positive, but this effectively disconnects the unilateral conductor at 105 from across line 102 because conduction at 114 in the anode circuit of the valve 85 makes the cross line 102 negative. Lines 104 and 106 are already maintained negative by virtue of the diode conduction occurring at 107 and 109 in the anode circuit of valve 63. However, since the valves 62

and 34 are nonconductive, making the cathodes of the diodes at 103 and 111 more positive, the diode end of the load 95 is free to also become positive with respect to the cross lines 102, 104, and 106. Thus, this arrangement of conductors and diodes may be regarded as a function table having the property of exciting the cross line 100 whenever the valves 62 and 84 are nonconductive, while maintaining the cross lines 102, 104, and 106 biased to an inoperative potential.

In the specific example being employed for illustrative purposes, it may be next assumed that a time sequence of intelligence-bearing impulses is impressed on the input of the transmission line 24 and propagated therealong, to be absorbed in the terminating load 92. For convenience it is assumed that the intelligence considered exists in the form of pulse groups spaced in time. As we have shown a delay line 24 with the taps 33 and 91 spaced by a single pulse time, it may be considered, in this simple illustration, that only two pulses are located within a given group. At the time when the leading pulse in the group would arrive, if present, at the delay line tap 91, a positive-going setup signal having a duration of one pulse time or less is impressed on the terminal 32, conditioning the coupling valves 21 and 83 for the passage of a signal to the associated flip-flop, if there is coincident excitation of the corresponding tap on the delay line at this instant. The coupling valves 21 and 83 therefore act as gates, with the inner electrode receiving a conditioning or alerting signal.

In the assumed case, an anode current surge is developed in the gating valve 21, resulting in the impression of a negative-going signal on control grid 42 of the flip-flop valve 48, interrupting conduction through this valve to develop at its anode 44 a positive-going stimulus applied to the auxiliary control grid 39 through the coupling network 53, which initiates conduction through this valve. This conduction reduces the potential at the anode 48 of the valve 21, to impress upon the auxiliary control grid 52 of the valve 48 through the coupling network 51, a negative signal maintaining the valve 48 in the off condition.

Since no signal appears at the transmission line terminal 91 during the alerting interval, the valve 83 remains inoperative and the flip-flop 82

With the flip-flop 20 in its abnormal state, the function table driver valve 63 is biased to cutoff by virtue of the potential drop occurring in the anode resistor 49, to which it is connected through a resistor 67, while no such drop occurs in the anode resistor 45, permitting conduction through the function table driver valve 62. Similarly, conduction continues through the function table driver valve 85 because of the relatively positive potential applied to its control grid. The conduction through the function table driver valve 62 reduces the potential of the anode 68 and the associated conductor connecting it with the load 70 to about seventeen volts negative with respect to ground, causing conduction through the unilateral conductors 103 and 105 holding the lines 100 and 102 at the minus seventeen volt level. The conduction through the valve 85 holds the cross lines 102 and 106 at substantially the same potentials for the same reasons. This leaves the line 104 unaffected by the conduction of the valves 62 and 85. The cross line 104 is connected through diodes at 107 and 112 with the anodes 69 and 88 of nonconducting

valves 63 and 84 which, by reason of their nonconduction, elevate the potential of the cathodes of the associated diodes positively, permitting the line 104 to assume ground potential through the resistor 97.

Other combinations of the reference and abnormal states in the flip-flops 20 and 82 will result in selection of other conductors from the group 100, 102, 104, and 106 in a manner which

10 may be readily derived in the light of the foregoing explanation.

The flip-flops 20 and 82 may be regarded as a register for the storage of information originally present in the form of a serial pulse train. They

15 are often referred to as a static register because this information remains present in the flip-flops until they have been deliberately reset. The network of conductors and diodes 100-106 has been referred to as a function table, this term being

20 chosen because of its property of uniquely selecting a single conductor as a function of the various input combinations which may be excited.

A function table such as that illustrated in Figure 1, which uniquely selects a single line in response to differing input combinations, may be conveniently referred to as a decoding function table, while function tables performing the inverse function of exciting groups of output conductors in response to the excitation of a single line may be conveniently referred to as an encoding function table.

The function table described in Figure 1 is of a type providing a positive-going indication on the selected line. Other function tables developing negative-going impulses on their output lines

35 are illustrated in Figure 2 which further develops the combined use of a plurality of function tables in performing a final selecting operation. The tables shown in Figure 2 select on the basis of combinations of conducting valves, while the table illustrated in Figure 1 performs its selection on the basis of combinations of nonconducting valves. The arrangement of Figure 2 includes a bank 145 of function table drivers including the

40 valves 121-128, whose anodes are connected respectively with the vertical lines 137-144, which are excited from the positive supply bus 120 through the loads 129-136 respectively. The cathodes of the function table driver valves in the bank 145 may be returned to the negative supply bus 61, while their space charge electrodes

45 are connected with ground. The control electrodes of these valves may be connected with a flip-flop static register of the type illustrated in Figure 1 through circuits similar to those there described. The cross-connecting or horizontal lines 150-159 are connected with the vertical lines 137-144 through unilateral conductors with the indicated sense at the points marked. These

50 connections are made in accordance with the following table:

Input Line	Driver Lines	Through Diodes at--
65		
137-----	150, 151, 152, 153, 154	161, 162, 163, 164, 165
138-----	155, 156, 157, 158, 159	166, 167, 168, 169, 170
139-----	150, 155, 156, 157, 158	171, 172, 173, 174, 175
140-----	151, 152, 153, 154, 159	180, 181, 182, 183, 184
141-----	151, 152, 155, 156, 150	185, 186, 187, 188, 189
142-----	150, 153, 154, 157, 153	192, 193, 194, 195, 196
143-----	151, 153, 155, 157, 159	197, 198, 199, 200, 201
144-----	150, 152, 154, 156, 155	202, 203, 204, 205, 206

75 The output lines 150 through 159 are individually returned through a bank of compensated resistive impedances at 211, having their other ends con-

nected with the negative supply bus 11. At their other extremity the output lines 150 through 159 connect individually with control electrodes of valves 260, 261, 262, 263, 264, 265, 266, 267, 268, and 269 respectively, which have their cathodes returned to ground and their space charge electrodes connected with the positive supply bus 60. The valves 260—269, inclusive, may be triodes or may be multiple grid valves, as illustrated. It will be noted that the unilateral conductor or diode connections correspond to the binary designation of the decimal numerals in an excess-three code, which is to say that the binary numbers expressed thereby are quantitatively equal to the decimal quantity to be expressed plus three.

The operation of the function table driven from the valve bank 145 is as follows: Each of the following groups of valves constitutes a pair, characterized by alternative conduction through one or the other of the pair members, in accordance with the setting of the flip-flop static register previously described; 121, 122; 123, 124; 125, 126; and 127, 128. Any set of conductive conditions satisfying the above limitations may be used as a reference state. It is assumed now that the flip-flop static register governing the valve bank 145 has been set up to produce the conduction pattern illustrated in Figure 2. The following valves are conductive: 121, 124, 125, and 128. This corresponds to the number 0101 in binary form which is expressed in the more familiar decimal notation as 5 but, since we are employing an excess-three code, representing the true decimal number 2. The selective negative energization of the cross line 152 takes place as follows: Conduction through the valve 121 reduces the potential on the line 137 to a relatively low value, somewhat negative with respect to ground, creating the possibility that one of the conductors 150, 151, 152, 153, or 154 may assume a negative potential. The valve 122 is nonconductive, whereby the conductor 138 is positive with respect to ground, producing conduction through the diodes 166, 167, 168, 169, and 170, thereby maintaining the lines 155, 156, 157, 158, and 159 positive with respect to ground and causing the valves 265, 266, 267, 268, and 269 to remain conductive, even though others of the vertical conductors may be negative with respect to ground. This is true because the application of a negative potential to the anode of any diode already associated with one of the positive lines just recited is effective merely to disconnect the diode presenting only its reverse impedance to the circuit. Hence, it will not be necessary to further consider diodes connected to the lines 155—159.

The valve 123 is likewise nonconductive, whereby conduction occurs through the diode 171 connected with the line 150, preventing this line from swinging negative. Next in order is the valve 124 which is conductive and the resulting negative potential on the line 140 connected with the load 132 develops negative potential across the diodes 180, 181, 182, and 183 which will not interfere with the negative excursion of any one of the lines 151, 152, 153, 154. Likewise, the valve 125 is conductive to reduce the potential on the vertical line 141, applying a negative potential to the diodes at 185 and 186, so that there is no interference at either of these points with the lines 151 or 152 assuming a negative potential. The lack of conduction through the valve 128 results in an elevation of the potential of the vertical line 142, producing conduction at the diodes 192, 193, and 194 preventing their associated lines 150, 153, and

154 from becoming negative. Likewise, the valve 127 is nonconductive so that the positive potential resulting at the line 143 initiates conduction through the diodes 197, 198 eliminating the lines 151 and 153 as possible negative conductors. The valve 128 is conductive, making the vertical line 144 negative whereby conduction is prevented through the diodes 202, 203, and 204.

A review of the conditions prevailing in the diode-conductor network illustrates that the line 150 is prevented by conduction through the diodes at 171, 192 from becoming negative. The line 151 is prevented by conduction through the diode at 197 from becoming negative. The line 153 is prevented by conduction through the diodes at 193 and 198 from becoming negative; the line 154 is prevented by conduction through the diode at 194 from becoming negative. Only the line 152 is connected through diodes at 163, 181, 186, and 203 with vertical lines having relatively negative potentials, whereby all the said diodes are effectively disconnected from the line 152, except for their reverse resistance, whereby the line is free to assume a potential of minus 11 volts through its associated individual load impedance. The line 152, distinguished on the diagram by its heavier appearance, upon becoming negative, interrupts the flow of current through the valve 262, developing a positive-going excursion in its anode circuit and the conductor connections associated therewith.

Completion of the selection is obtained through the use of a second function table driven from the valve bank 212, consisting of valves driving the vertical conductors 213, 214, 215, 216, 217, 218, 219, and 220 which are returned to the positive supply bus 120 through a bank of individual compensated load impedances 210. A number of unilateral conductors connected at the places indicated with the polarity shown connect the vertical or input lines with the horizontal or output conductors 230, 231, 232, 233, 234, 235, 236, 237, 238, and 239 returned through individual members of the impedance bank 252 to a potential of minus 11 volts.

Selection of one of the horizontal conductors in accordance with the pattern of conduction and nonconduction in the valve bank 212 is performed in the same manner as was developed in connection with the previous function table driven from the valve bank 145. The conduction pattern in the bank 212 is illustrated as setting up the binary number 1001, which is equivalent to the decimal number 9, or, bearing in mind that the excess-three code has been employed, 6. The heavy line conductor 236 is therefore permitted to swing negatively.

It will be noted that the conductors 230—239 are coupled in pairs to the control elements of the valves 250, 252, 254, 256, and 258 through the individual diodes 240—249, poled to pass negative-going impulses. Negative excursion of the line 236 initiates conduction in the diode 246, placing a negative potential on the control electrode of valve 256 to interrupt the flow of anode current therethrough, causing a positive voltage excursion in the anode circuit and conductors associated therewith. This line is accented in Figure 2.

The various connections shown emanating from the anode lines associated with the valves 260—269 and 250, 252, 254, 256, and 258 are connected in pairs to coincidence selecting circuits of the same or other types where a gating function may be performed on any desired circuit.

Preparatory to the showing and discussion of a more complex switching and selecting organization, such as might be employed in connection with a high speed electronic computer, the organization of Figure 3, illustrating a three-stage static register, similar in its construction and properties to the register of Figure 1 has been illustrated. A coupling gate 304 is connected with the junction 301 on a two-section transmission line 324, and the output of the gating valve 304 may be connected with one side of the flip-flop 305.

Another coupling gate 306 has its auxiliary control electrode connected with the junction point 302 on the transmission line 324 and its output connected with the left-hand side of the flip-flop 307. A third coupling valve 308 also has its auxiliary control electrode connected with the junction 303 on the transmission line 324, and its output is delivered to the left-hand side of the flip-flop 309.

The inner grids of the coupling gates 304, 306, and 308 are connected together and, through the capacitor 33, to the setup signal input terminal 32, which is excited by a stimulus related to the signals applied to the transmission line 324 in a fashion similar to that already described in connection with Figure 1. The auxiliary control grids of the flip-flops 305, 307, and 309 are connected through appropriate impedances with the negative supply bus 191. The inner control grids of the right-hand valves of the flip-flops 305, 307, and 309 are connected together and to the clearing bus 356 returned to the cathode supply bus through resistor 357 and connected with one pole of the single-pole double-throw switch 258, whose other pole is connected with the negative supply bus 191, while the movable contact is returned to ground through capacitor 359. The flip-flop 305 excites the function table driver valves 320 and 321, while the flip-flop 307 excites the function table driver valves 322 and 323 while flip-flop 309 excites corresponding function table driver valves 324 and 325. When this assembly is in its reference state, the left-hand sides of the flip-flops 305, 307, 309 are conducting, as are the valves 321, 323, and 325.

The driver valve 320 is connected via the line 349 and resistor 330 to the positive supply bus 120. In addition, the valves 321, 322, 323, 324, 325, respectively, are connected over the lines 341, 342, 343, 344, and 345, respectively, with the positive supply bus 120 through resistors 331, 332, 333, 334, and 335 respectively. Unilateral conductors are connected at the points and in the senses shown, whereby unique combinations of conducting valves select one of the output conductors 360, 361, 362, 363, 364, 365, 366, or 367. The operation of this register and associated function table is so similar to the operation of the apparatus in Figure 1 as to preclude the necessity of a detailed repetition of the operating details at this point.

Suffice it to say that the combination permits the selection of one output conductor for each unique combination of the distribution of the states of conductivity and nonconductivity in the register.

The foregoing function tables of Figures 1 and 3 together with their associated driving equipment have been characterized by perfect symmetry. The arrangement of Figure 4 illustrates a counter chain driving a function table network, in which the alternatively conductive members of the counter stages, whose internal structure is much like that of the flip-flops previously de-

scribed, excite an array of valves connected with the input lines of the function table.

Negative-going counter driving impulses are impressed on the input terminal 429 and applied through capacitor 419 to the control grid of the coupling valve 416 having the resistor 418 in its cathode circuit. The control grid is returned to the negative bus 41 through the resistor 421 and the cathode 417 is connected with the negative supply bus 191 through the said resistor 418, making the valve 416 normally conductive.

Each counter stage employed may, as in the case illustrated for the stage 399, consist of a dual triode assembly within a common envelope 400. The cathodes 401 and 402 are returned to the negative supply bus 141 and the control grid 403 of the left-hand triode is connected through the resistance-capacitance network 409 to the anode 408 of the right-hand valve, in addition to being connected with the cathode of the diode 422, and through the resistor 411 to the negative supply bus 191. Similarly, the control grid 404 of the right-hand valve section is linked through the resistance-capacitance network 408 with the anode 405 of the left-hand valve assembly. In addition, the anode 405 may be connected with ground through a load resistance 415 and the anode 406 may be connected with ground through the load resistance 414. A diode 413 has its anode connected with the anode 405 and cathode connected with the cathode 417 of the input valve 418. The anode 406 is similarly connected through a diode 412 with the cathode 417. The anode of the diode 422 is connected with the clearing bus 423, which is supplied with positive-going impulses to establish the desired reference pattern of conduction in the array of counter elements. The remaining stages of the counter are indicated at 424, 425, 426, 427, and 428 with the sides conducting in the reference state shaded. These units are similarly connected with the clearing bus 423 by diodes which form a part of their internal structure and are interconnected by driving lines exciting the counterpart of the valve 416 within the individual assemblies.

The function table input conductors 440, 441, 442, 443, 444, 445, 446, 447, and 448 are excited from a series of driver valves 430, 431, 432, 433, 434, 435, 436, 437, and 438. Each of the function table driver valves is returned to the positive bus 80 through an individual load resistor and is provided with clamping diodes arranged in the manner described in connection with Figures 1 and 3. The counter stage 399 governs conduction in driver valves 430 and 431 through the connection of their respective control electrodes with the anodes 405 and 406. In like manner, the flip-flop 424 governs conduction in the coupling valves 432 and 433, while the flip-flops 425, 426, and 427 respectively govern the valves 434, 435, and 436. The last stage 428 in the counter chain also controls two driver valves 437 and 438.

The vertical line 440 is connected with the lines 460, 461, and 463 through the diodes 491, 492, and 493, and vertical line 441 is linked to the horizontal line 462 by diode 499. In addition, the diodes 487, 488, and 489 connect the horizontal lines 460, 462, and 463, with the lines 442 and the diode 486 connects the vertical line 443 with the horizontal line 461. Each of the vertical lines 444, 445, 446 is connected to all the horizontal lines 460, 461, 462, and 463 through one of the diodes in the group 474-485. Vertical line 447 is linked with the horizontal line 460 by the diode 473 and the vertical line 448 is connected

with horizontal lines 461, 462, and 463 through the diodes 470, 471, and 472.

The resetting circuit includes the valves 495, 507 and is excited with positive-going impulses through an input capacitor 499 coupled with the cathode 496 of the diode connected triode assembly having electrodes 497. A resistor 508 connects the diode-anode electrode group 427 with the negative supply bus 101 and a capacitor 498 connects this point with the negative supply bus 191. The cathode 496 is also returned to this supply bus through the resistor 494. The potentials impressed on the left-hand electrode assembly make this section of the valve 495 normally conductive. However, the clearing impulses periodically applied through the capacitor 499 charge the capacitor 498 with a polarity tending to diminish or cut off said conduction. The control grid 501 of the right-hand section of the valve 495 is connected with the grid-anode 497 and the anode 502 of the right-hand section of valve 495 is connected through the resistor 503 with the negative supply bus 101 and to the control electrode 504 of the normally conductive clearing valve 507 which has its anode connected to the negative supply bus 61 and its cathode connected through the resistor 506 with the negative supply bus 191. The cathode 500 of the right-hand section of the valve 495 is also connected to this negative supply bus 191. The valve assembly 500, 501, 502 and the valve 507 are normally conductive.

In operation, the counter chain is actuated by a selected train of impulses derived from any suitable source such as a computer selecting gate. The counting chain is in the illustrated state at the beginning of a counting sequence due to the forced positive excursion of the clearing line 423. The arriving negative-going impulse passes through the short time constant circuit 419, 421 and diminishes or cuts off the flow of current through the resistor 418 in the cathode circuit of the input valve 416, permitting the cathode end of this resistor to become more negative, which potential shift is transmitted through the diode 412 to the anode 406, where it initiates the changeover process transferring conduction from the left-hand side to the right-hand side of the flip-flop 399. This develops a negative-going impulse delivered to the input of the stage 424 to initiate therein the same sequence of events which in turn triggers off flip-flops 425, 426, 427, and 428. Successively arriving impulses cause continued operation of the counting chain in a manner familiar to those skilled in the art. The standby state corresponds to a number expressed in binary notation as 11111, or, decimal, 63, and in this state the horizontal line 460 in the function table is maintained at ground potential or a few volts positive with respect thereto. For the next 28 counts no output line from the function table is energized, whereby all remain at a potential of about minus 17 volts with respect to ground. On the twenty-ninth count, the combination 011101 (equals 29) is set up in the register and the line 461 swings positively to ground potential or slightly above. The next count sets up the combination 011110=30 and makes the line 462 positive with respect to ground, while the next count sets up the combination 011111=31 and changes the potential of the horizontal conductor 463 to one slightly positive with respect to ground. These are employed in conjunction with the outputs of the previously described registers to select individual control

lines to perform the various sequences required in the execution of desired switching operations.

Thereafter, a negative-going impulse is applied to the capacitor 499 to charge the capacitor 498 through the diode in the valve 495 and bias the control grid 501 in valve 495 to cutoff, making the potential of the anode 502 and the control grid 504 of the valve 507 connected therewith more positive. This develops a positive-going impulse across the cathode resistor 506 associated with the valve 507 which is impressed on the anode of the diode 422 and its counterparts in the other flip-flops to cause the left-hand side of the flip-flops 399 and 424 through 428 to become conductive.

The auxiliary decoding function tables which have been described in connection with Figures 1, 3 and 4 may be connected with a main decoding function table such as that shown in Figure 5, where the function table of Figure 1 is presented at the upper left-hand corner, the function table of Figure 3 appears centrally in the bottom portion of the drawing and the function table of Figure 4 is repeated at the upper right-hand portion of the drawing. Identity of reference characters has been observed throughout in this drawing. The output conductors of the decoding function table of Figure 5 are numbered 600 through 622 and are designated as well by letter abbreviations for the function to which they correspond. These lines are individually returned through resistors 625 through 647, respectively, to positive supply lines of the potential indicated. Diodes connect the various input lines with the main decoding function table output lines 600-622 at the points indicated. It may here be noted that the output lines of the associated function tables are directly connected with the input to the main decoding function table, and, hence, also represent input lines for the auxiliary tables. This is in contrast with the arrangement of Figure 2 which interposed buffer valves between the output lines of the auxiliary function tables and the input lines to the main decoding function table.

It will further be noted that the supply potentials to which the main decoding function table output lines are connected vary over the range plus 60 to plus 160 volts. The magnitude of the resistors 625 through 647 also varies somewhat, though not over the same range. For example, the resistors 625, 626, 627, 629, 635, 636, 637, 639, 640, 642, 644, 645, 646, and 647 may have a magnitude of 15,000 ohms, while the resistor 628 may have a value of 12,500 ohms; 630, 633, 634, 641, and 643, may have a value of 12,000 ohms, and the resistors 631, 632, and 638 may have a value of 10,000 ohms.

The significance of the different voltages and resistances becomes fully apparent only when Figure 5 is studied in conjunction with the following Figure 6. In anticipation of the presentation of that figure it may be remarked that the differing voltages and resistances are proportioned in accordance with the expected load presented by the apparatus in Figure 6 in the form of diode back resistances and other current-consuming elements.

No attempt will be made to describe each of the output possibilities, it being felt that the development of these possibilities for one or two cases should establish the rule for further independent investigation thereof.

For example, if the lines 100 and 365 enjoy a

positive excursion, the line 600 also becomes positive, the balance of the lines remaining at about minus 17 volts with respect to ground. This corresponds to conduction in the valves 63 and 85 of Figure 1 and of the valves 329, 323, and 324 in Figure 3. The excitation of the line 600 is independent of the conductivity pattern in the apparatus of Figure 4. If now the lines 100 and 363 become positive, the selected line will be 602 or 604, depending upon the conduction pattern within the apparatus of Figure 4. Since the apparatus of Figure 4 is performing a counting operation the line 602 will first be energized, followed by energization of the lines 604. During this cycling operation, the rest of the output lines from the decoding function table of Figure 5 remain at approximately minus 17 volts with respect to ground.

The various combinations possible in the apparatus already described have now been resolved into the selective excitation of one of a large number of conductors. As a result of this selective excitation, it is now desired to energize a controlled pattern of many conductors, and the network so far described is therefore connected with the apparatus of Figure 6 whose horizontal conductors represent input conductors and are identified by the reference characters appearing in Figure 5. This one-to-many, or encoding, function table has lines 461 and 600 through 622 inclusive as its output conductors. The output voltages are developed across individual members of a bank of resistors 700 having one end returned to the negative supply bus 11. The lines 655 and 656 are connected to the anodes of a pair of diodes 687 and 688 whose cathodes are connected together and to one of the output resistors. Similarly, the output lines 659, 660, and 661 are connected with the anodes of diodes 693, 690, and 691 whose cathodes are joined together to a single output resistor. The lines 672, 673, and 674 are similarly connected through diodes 692, 693, and 694, the lines 677 and 678 being similarly tied through the diodes 695 and 696, and the lines 684, and 685 through the diodes 697 and 698.

Since the resistor associated with the cathodes of such pairs of diodes experiences a positive potential when either of the function table output lines associated therewith becomes positive, these diode connections may be regarded as buffer connections. For example, the positive excitation of the line 600 excites output conductors 655, 678, and 685, making the associated output resistor terminal positive and impressing on the companion diodes 683, 695, and 697 a reserve potential whereby the diode presents its reverse resistance, minimizing leakage current through the associated diode networks, which would tend to reduce the maximum output voltage available. In connection with the selection of loading resistors and voltages previously discussed, it may be noted that the line 600 has associated with it three diodes feeding branch circuits including eight diodes and is connected to the positive supply bus 120 through a 15,000 ohm resistor 625. On the other hand, the line 603 has associated therewith seven diodes feeding branch circuits having a total of nine diodes for which back current is to be supplied. Because of the greater 70 back current requirements, this line is returned to the positive supply bus 160 through a 12,500 ohm resistor. The loading on this line would be even heavier were it not for the interposition of the buffer diodes 687, 689, and 690, replacing 75

the back resistance of three diodes with the back resistance of a single diode.

The function table selecting network described supplies a convenient and high speed means for translating multiple coded inputs into one or many arbitrarily coded outputs. Their utility is considerable and they may be employed in many environments with such modification as the circumstances indicate to be desirable. Heater and anode supply circuits for operating the electric valves shown herein have been omitted, as any of the well known configurations of this type may be used in the practice of the invention.

It will be obvious to those skilled in the art 15 that the invention may find wide application with appropriate modification to the individual design circumstances, but without substantial departure from the essence of the invention.

What is claimed is:

- 20 1. In combination, first and second potential supply conductors, an electric valve connected in series with a load impedance between said supply conductors, a first unilateral conductor connected in a first sense between the valve end of said first load impedance and a first reference potential conductor, a second unilateral conductor connected in reverse sense between the valve end of said first load impedance and a second reference potential conductor, a signal line, a second impedance connected between said signal line and a supply conductor, and a third unilateral conductor operatively connecting said signal line with the junction between said first and second unilateral conductors.
- 25 35 2. In combination, a plurality of electric networks individually characterized by at least two mutually exclusive stable electric states, a source of reference signals placing each of said networks in one of its stable states, a transmission line characterized by delay of the signals transmitted therewith, connections extending individually from spaced regions on said transmission line to selected ones of said electric networks whereby transmission line impulses induce the other of said stable states therein, a plurality of signal lines individually returned through bilateral impedances to reference potentials, a plurality of selecting lines adapted to vary in potential under the control of said electric networks, a first set of unilateral conductors connecting selected members of said signal lines with selected members of said selecting lines in unique combinations, a second set of unilateral conductors connecting in a first sense said selecting lines to first reference potential conductors, and a third set of unilateral conductors connecting in reverse sense said selecting lines to second reference potential conductors.
- 40 45 55 3. In combination, a first selecting network having input and output conductors adapted to receive a plurality of stimuli over a corresponding plurality of input conductors and uniquely energize a single output conductor in response to unique input combinations, a second selecting network having input and output conductors adapted to receive a plurality of stimuli over a corresponding plurality of input conductors and uniquely energize a single output conductor in response to unique input combinations, impedances individually connecting said input conductors to a source of electric energy, first unilateral conductors connecting in a first sense said input conductors to first reference potential conductors, second unilateral conductors in series with impedances connecting in reverse sense said

input conductors to second reference potential conductors, a third selecting network comprising the output conductors of said first and second networks as input elements and having a plurality of output conductors separately and individually excited in response to unique input combinations, and a fourth selecting network comprising the output conductors of said third selecting network as input conductors and having a plurality of output conductors excited in unique combinations in response to the excitation of individual input conductors.

4. In combination, a first selecting network comprising a plurality of input conductors connected with corresponding electric valves and a plurality of output conductors separately and individually excited in response to unique input combinations, impedances individually connecting said input conductors with a source of electric energy, a second selecting network comprising a plurality of input conductors connected with a second set of corresponding electric valves and a plurality of output conductors separately and individually excited in response to unique input combinations, impedances individually connecting said second input conductors with a source of electric energy first unilateral conductors connecting in a first sense said input conductors to first reference potential conductors, second unilateral conductors connecting in reverse sense said input conductors to second reference potential conductors, a third selecting network comprising the output conductors of said first and second networks as input elements and having a plurality of output conductors separately and individually excited in response to unique input combinations, a fourth selecting network comprising the output conductors of said third selecting network as input conductors and having a plurality of output conductors excited in unique combinations in response to the excitation of individual input conductors, and impedances individually connecting the output conductors of said third network with voltage levels varying systematically with variation in the number of fourth network output conductors excited by said third network output conductors.

5. In selective signaling apparatus, a plurality of input conductors, a plurality of intermediate conductors, a first group of unilateral conductors connected in a first sense between a first group of said input conductors and a first group of said intermediate conductors, a second group of unilateral conductors connected in said first sense between a second group of said input conductors and a second group of said intermediate conductors, an output conductor, unilateral conductors connected in said first sense between said intermediate conductors and said output conductor, and electronic switching means respectively connected to said input conductors, said intermediate conductors and said output conductors for selective actuation thereof.

6. In combination, first and second pairs of alternatively conducting electric valves, conducting members individually connected with said valves, means to apply operating potentials through said conducting members to said valves, a first reference potential conductor connected through a unilateral conductor in a first sense to each of said conducting members, a second reference potential conductor connected through a unilateral conductor in reverse sense to each of said conducting members, an output set of four conducting members, a

first group of unilateral conductors connecting the first and second of said output conducting members with one of the members of said first valve pair, a second group of unilateral conductors connecting the third and fourth of said output conductors with the other of the members of said first valve pair, a third group of unilateral conductors connecting the first and third of said output conductors with one of the members of said second valve pair, and a fourth group of unilateral conductors connecting the second and fourth of said output conductors with the other of the members of said second valve pair.

7. In combination, a first plurality of conducting members, individually connected with electric valves, resistances of predetermined magnitude individually connected between electric supply points and said first conducting members, first and second reference potential conductors, unilateral conductors connecting in a first sense said conducting members to said first reference potential conductors, unilateral conductors connecting in reverse sense said conducting members to said second reference potential conductors, a second plurality of conducting members, unilateral conductors linking selected ones of said first plurality of conducting members with selected ones of said second plurality of conducting members, and resistances having a magnitude not greater than one-fifth the magnitude of said first resistances individually connecting the conductors of said second group with electric supply points.

8. In combination, a first set of input conductors, a first set of output conductors, unilateral conductors interconnecting selected members of said first set of input conductors and selected members of said first set of output conductors, a second set of input conductors, a second set of output conductors, unilateral conductors interconnecting selected members of said second set of input conductors and selected members of said second set of output conductors, first and second reference potential conductors, unilateral conductors connecting in a first sense said input conductors to said first reference potential conductors, unilateral conductors connecting in reverse sense said input conductors to said second reference potential conductors, a third set of output conductors, unilateral conductors linking selected members of said first and second sets of output conductors with selected members of said third set of output conductors, resistances connecting individual ones of said third set of output conductors with electric supply points, a fourth set of output conductors, and unilateral conductors connecting selected members of said third set of output conductors with selected members of said fourth set of output conductors.

9. In combination, a plurality of conductor pairs, a like plurality of electronic switching means, means to apply an operating potential to the output of the corresponding switching means, means to apply high-frequency actuating signals to the input of each of said switching means to symmetrically excite each conductor pair, an additional plurality of individual conductors, a first array of unilateral conductors connected between selected members of said pairs and said individual conductors in a given sense, a second array of unilateral conductors connected between different selected members of said pairs and said individual conductors, a third array of unilateral conductors connecting in a first sense each member of said conductor pairs to a first

reference potential conductor, and a fourth array of unilateral conductors connecting in reverse sense each member of said conductor pairs to a second reference potential conductor.

10. First and second potential supply conductors, a plurality of pairs of electric valves, each member of said pairs being alternately conductive and connected in series with an impedance between said supply conductors, a plurality of signal lines individually returned through associated impedances to third supply conductors, a first set of unilateral conductors interposed between each member of said pairs of electric valves and selected ones of said signal lines in individual unique combinations, first and second reference potential conductors, a second set of unilateral conductors connecting in a first sense the members of said pairs of electric valves to said first reference potential conductors, and a third set of unilateral conductors connecting in reverse sense the members of said pairs of electric valves to said second reference potential conductors.

11. In combination, a plurality of input conductors, a plurality of output conductors, unilateral conductors connecting individual ones of said input conductors with variably sized groups of said output conductors, energizable exciting circuits connected with said input conductors, first unilateral conductors connecting in a first

5 sense members of said energizable exciting circuits to first reference potential supply conductors, second unilateral conductors connecting in reverse sense said members to second reference potential supply conductors, means to apply an operating potential to said members, means connected with said energizable exciting circuits to effect selective energization thereof, and impedances connected between said input conductors and electric potentials, the magnitude of said potentials and said impedances being selected to develop substantially equal voltages at said input conductors.

10 15 12. The combination according to claim 11 in which the voltage levels of said potentials vary systematically with the number of unilateral conductors connected to the associated input conductors.
